UNITED STATES PATENT OFFICE.

JOHN WICKS, OF CHICAGO, ILLINOIS, ASSIGNOR TO AUTOMATIC ELECTRIC COMPANY, OF CHICAGO, ILLINOIS, A CORPORATION OF ILLINOIS.

MULTIOFFICE TELEPHONE SYSTEM.

Application filed January 20, 1922. Serial No. 530,502.

To all whom it may concern:

Be it known that I, JOHN WICKS, a citizen of the United States of America, and a resident of Chicago, Cook County, and State 5 of Illinois, have invented certain new and useful Improvements in Multioffice Telephone Systems, of which the following is a specification.

The present invention relates to multi- 10 office telephone systems in general, but is concerned more particularly with such systems as comprise both manual and automatic offices, and the object of the invention, broadly stated, is the provision of new and 15 improved arrangements for handling calls which originate at a manual office and which are intended for subscribers of automatic offices.

The invention is particularly applicable 20 to multi-office systems that are being changed, an office at a time, according to common practice, from manual to automatic operation. In order to effect such a change, the "A" operators, in each of the 25 manual offices that are to remain manual for the time being, are provided with the necessary equipment for extending calls to each of the automatic offices. It is, therefore, an object of the invention to provide 30 the "A" operators with efficient and easily manipulated apparatus for extending calls to automatic offices. It is a further object to provide a few senders which are common to a great many operators. There are various other objects not specifically mentioned now, all of which will be pointed out 35 and fully explained hereinafter, with reference to the accompanying drawings.

For an understanding of the circuits, 40 Figs. 1, 2, and 3 of the drawings should be laid out in order with the corresponding lines at the ends thereof in alignment; Figs. 4 and 5 should be placed in order with the corresponding lines at the ends thereof in 45 alignment and with the conductors on Fig. 5, that are turned up, in alignment with the corresponding conductors on Fig. 2 that are turned down; and Figs. 6, 7, and 8 should be placed in order with the corresponding 50 lines at the ends thereof in alignment, with Fig. 7 directly under Fig. 4, and with the corresponding inter-connecting lines between the two figures in alignment. When thus arranged, the drawings show sufficient 55 equipment for a complete connection from a

calling manual substation A, Fig. 1, to a called automatic substation A', Fig. 3, together with the necessary equipment at the "A" operator's position for controlling the automatic switches. It will be noted that 60 the connection, when established, includes the calling substation A and associated line, the cord circuit O, an outgoing trunk passing through the trunk equipment T, a secondary distributing switch C, automatic repeater E, selector D, connector H, line switch C', and the called automatic substation A' and associated line. The apparatus shown in the remaining figures is not included in the talking connection and is used 65 merely to control the automatic switches. 70

The equipment shown in Fig. 1, comprising the substation A, the associated line and jacks, and the operator's cord circuit O, is standard manual equipment such as is in 75 common use. The trunk on the right-hand side of Fig. 1, which terminates in the jacks J² and J³, is provided with an indicating lamp at each of the jacks for a purpose to be hereinafter explained. 80

The trunk relays T, Fig. 2, are used as a means for switching the trunk from the control of the operator's sender to the control of the operator's cord circuit. 85

The secondary distributing switch C is 90 mechanically the same as a rotary line switch and, accordingly, the wipers have no normal position and move in a forward direction only. A few slight circuit changes, however, have been made in order 95 to enable this switch to function properly as a secondary switch.

The automatic repeater E is used to repeat impulses forward and also to translate the reverse battery supervision of the automatic switches into high resistance supervision for the manual equipment. 95

The selector D, Fig. 3, is an automatic selector switch of the well known vertical and rotary type in which the bank contacts 100 are arranged in horizontal rows or levels. The circuits and functions of this switch are well known and accordingly do not need to be described herein.

The connector H is mechanically the same 105 as the selector D. Most of the circuits of this connector have been omitted for the sake of simplicity, only the line release and back bridge relays being shown.

The line switch C' is a rotary line switch 110

of the well known type in which the wipers have no normal position and move in a forward direction only.

5 The called substation A' is an automatic substation of the well known type, having the usual, talking, signalling, and switch controlling instrumentalities.

10 A detailed description of automatic switches such as are referred to above comprising the selector D, connector H, and the line switch C, may be found in "Automatic Telephony" which is a book by Smith and Campbell and is published by McGraw-Hill Book Company, New York, N. Y.

15 The trunk selector TS, Fig. 5, is mechanically identical with the rotary line switch C', Fig. 3, just described. The circuits of this switch, however, have been altered to meet the different requirements under which 20 it must operate. The trunk selecting switch TS' is identical with the trunk selecting switch TS. The switch TS is assumed to have access to trunks leading to automatic office No. 1, and the switch TS' is assumed 25 to have access to trunks leading to automatic office No. 2.

30 The sender selector SS, associated with the trunk selectors TS and TS', is mechanically identical with either of the latter with the exception that, since the number of 35 wipers carried by this switch is larger than can be conveniently mounted on the particular mechanical embodiment of the switch used, the wipers have been arbitrarily divided into two parts, one part being mounted on one switch frame, and the other part being mounted on an adjacent switch frame. The two operating magnets 263 and 264 are operated synchronously in a manner 40 to be explained fully hereinafter.

45 Of the operator's calling push buttons shown in the upper left-hand corner of Fig. 5, the first two, 221 and 222, are used to select either of the two switches TS or TS'. The next ten buttons, comprising buttons 50 201-210, inclusive, are used by the operator in setting up the digits of the number after the desired office has been selected by operating either of the buttons 221 or 222. The last push button 215 is a release push button and is used to release a partly set up number before it is sent out, in case the operator discovers that she has made a mistake and pushed the wrong button.

55 The translating and controlled relays, Fig. 4, are used primarily to permit a reduction in the number of wipers carried by the sender selector SS. The functions of these relays will become more apparent upon 60 a further perusal of the specification.

65 The counting switch CS, Fig. 6, is mechanically identical with any of the other rotary switches shown, such as the switches TS and TS', Fig. 5. The function of this switch is to count the impulses, as they are

being sent, and to switch over to the next digit when a sufficient number of impulses have been sent in any one digit.

70 Fig. 7 shows the storage relays for storing up the second digit, as the number is being set up by the operator. Fig. 8 shows duplicate equipment for storing up the third digit. It will be understood that the storage sets for storing up each of the remaining digits are exact duplicates of Fig. 8. 75

80 The apparatus, having been described more or less in general, will now be described in connection with a detailed description of its operation. For this purpose it will be assumed that the subscriber at substation A desires to converse with the subscriber at substation A' whose line terminates in automatic office No. 1 and whose number will be assumed to be 1456. When the receiver is removed at substation A, a 85 circuit is closed over line conductors 2 and 3 for line relay 6. Line relay 6, upon energizing closes a circuit for the lamp L. The operator, upon observing the lighted condition of lamp L, inserts an answering plug 90 of an idle cord circuit into the jack J, the plug P of the cord circuit O, for example, thereby closing the circuit for cut off relay 5 in series with supervisory lamp L'. Cut off relay 5, upon energizing, disconnects the 95 line conductors 2 and 3 from ground and from line relay 6, respectively, whereupon the said line relay 6 becomes deenergized and the lamp L becomes extinguished. Supervisory relay 7 in the cord circuit O, upon 100 energizing over the calling line, places a shunt around the supervisory lamp L' so as to prevent the said lamp from becoming lighted at this time.

105 The operator now throws her key K, which is a combined listening and ringing key, into listening position, thereby connecting up her head set so as to enable her to converse with the calling subscriber. The calling subscriber now tells the operator 110 with which subscriber he desires to be connected, and upon learning that it is the subscriber at substation A' in the automatic office No. 1, the operator restores the key K to normal, and operates the office selecting push button 221, Fig. 5, which button corresponds to the first digit 1 of the desired number. Upon being operated, push button 221 closes the following circuit: from ground by way of said push button 221, conductor 226, armature 241 and its resting contact, and the upper winding of relay 280 of the trunk selecting switch TS to battery. Relay 280, upon energizing, prepares a circuit for switching relay 251 115 at armature 288; and at armature 283 closes the following circuit: from ground by way of the normally closed contacts controlled by armature 277 of relay 269, armature 283 and its working contact, switching relay 268, 120 125 130

armatures 265 and 266 and their resting contacts, and stepping relay 267 to battery. As a still further result of the energization of relay 280, it connects test wiper 350 of the 5 sender selector SS to a point in the circuit between switching relay 268 and stepping relay 267, at armature 284. Assuming that the wipers of the switch SS are standing upon a busy sender, switching relay 268 is 10 short circuited and stepping relay 267, upon energizing, closes a locking circuit for itself at armature 270, and at armature 271 and 272 closes the circuits of stepping magnets 263 and 264. Upon energizing, each of the 15 said magnets attracts its armature so as to cause the associated pawl to engage the next notch on the wiper driving ratchet wheel. Upon both magnets completing their stroke, the circuit of stepping relay 267 is opened 20 at armatures 265 and 266, and the said relay 267, upon deenergizing, opens the circuits of the magnets 263 and 264, whereupon the said magnets deenergize, thereby driving the wipers 243-350, inclusive, into engagement 25 with the next set of contacts and connecting up the stepping relay 267 again at armatures 265 and 266. This alternate operation of stepping relay 267 and stepping magnets 263 and 264 continues until the wipers have 30 arrived upon a set of contacts in which the conductors associated with an idle sender terminate.

When an idle set of contacts is reached, which set we shall assume is the one shown 35 in the drawings, switching relay 268, being no longer short circuited, energizes over its previously traced circuit in series with stepping relay 267. The latter relay, however, does not energize at this time owing to the 40 high resistance of switching relay 268. Switching relay 268, upon energizing, opens the test circuit and places ground upon test wiper 350 at armature 274, thereby making the seized sender busy immediately. As a 45 further result of the energization of switching relay 268, it connects up wiper 349 at armature 273; places ground upon armature 289 of the trunk selector TS at armature 275; prepares a locking circuit for relay 50 280 of the switch TS at armature 276; and at armatures 253' and 252', connects ground and battery to conductors 223 and 224, respectively. This is done so as to render the operator's set up push button set operative. 55 In the translating relays, Fig. 4, the grounding of conductor 158 by the switch SS, as explained above, closes a circuit for relay 103 by way of the normally closed contacts controlled by armature 106. Relay 60 103, upon energizing, closes at armature 113 the following circuit: from ground by way of the working contact of armature 113 and said armature, upper winding of relay 104, relays 122, 124, 126, 128 and 130 in multiple, 65 relays 121, 123, 125, 127 and 129 in multiple, and the lower winding of relay 104 to battery. The relays 121-130, inclusive, are very stiffly adjusted and consequently none of them energize at this time, and relay 104 does not energize at this time because it is 70 differentially wound. As a further result of the energization of relay 103, it prepares a locking circuit for itself at armature 112, and at armature 111 places ground upon conductor 167, thereby closing the following 75 circuit: from ground, by way of grounded conductor 167, armature 420 of relay 408, Fig. 6, and its resting contact, normally closed contacts controlled by armature 423, conductor 424, resting contact of armature 80 459 and said armature, relay 453, and relay 454 to battery. Relays 453 and 454, upon energizing, connect up conductors 141-150, inclusive, to relays 471-480, inclusive, respectively, at armatures 461-470, inclusive, 85 respectively. The sender is now in condition to receive the number as it is set up. Returning now to the switch TS, Fig. 5, as a further result of the energization of 90 relay 280 in response to the operation of push button 221, it closes a circuit for switching relay 281 and rotary magnet 282 in series, at armature 286; and at armature 287 connects test wiper 304 to a point between said switching relay 281 and said 95 stepping magnet 282. From this point the operation depends upon whether the trunk upon which the wipers 301-304, inclusive, are standing, is busy or idle. If it is idle, 100 switching relay 281 energizes immediately, but if it is busy there is a ground potential upon the test contact thereof; relay 281 is short circuited; and stepping magnet 282, which interrupts its own circuit, is operated 105 in the manner of a buzzer to advance the switch wipers step by step in search of an idle trunk. Assuming that the trunk to which the conductors 305-308, inclusive, extend is the first one found to be idle, 110 switching relay 281 is no longer short circuited when the switch wipers arrive upon the contacts in which these conductors terminate and accordingly energizes. Stepping magnet 282, however, does not energize at 115 this time owing to the high resistance of switching relay 281. Switching relay 281, upon energizing, opens the testing circuit and places direct ground on test wiper 304 at armature 292, thereby making the seized trunk busy immediately; connects up wiper 120 303 to relay 269 at armature 211; and at armature 294 completes the following locking circuit for relay 280. From ground by way of armature 276 of relay 268 and its working contact, armature 294 and its 125 working contact, armature 285 and its working contact, and the lower winding of relay 280 to battery. As a further result of the energization of relay 281, it connects up wiper 301 at armature 289, thereby closing 130

the following circuit for the indicating lamp L^4 , Fig. 1: from ground by way of armature 275 and its working contact of switching relay 268, armature 289 and its working contact, wiper 301, the contact with which it is in engagement, conductor 305, and indicating lamp L^4 to battery. As a still further result of the energization of switching relay 281, it connects up wiper 302 at armature 290, thereby closing the following circuit: from ground by way of the normally closed contacts controlled by armature 279, armature 290 and its working contact, wiper 302, the contact with which it is in engagement, conductor 306, armature 36 and its resting contact, normally closed contacts controlled by armature 28, armature 53 and its resting contact, and line relay 51 to battery. Line relay 51, upon energizing, closes a circuit for switching relay 50 and stepping magnet 52 in series at armature 58, and at armature 57 connects test wiper 61 to the magnet 52. The switch C now operates in well known manner to pick out an idle trunk line, being driven step by step by the buzzer like action of stepping magnet 52, and, upon arriving upon an idle trunk, which trunk we shall assume is the one comprising conductors 63-65, inclusive, does not rotate any further owing to the absence of ground on test conductor 64. When this occurs, switching relay 50, being no longer short circuited, energizes in series with stepping magnet 52. Stepping magnet 52, however, does not energize at this time owing to the high resistance of switching relay 50. Switching relay 40, upon energizing, opens the set circuit and prepares the holding circuit at armature 54; places a multiple ground upon test conductor 308 at armature 55; and at armatures 53 and 56 disconnects the upper and lower conductors of the trunk from the winding of line relay 51 and ground, respectively, and extends them by way of wipers 60 and 62, the contacts with which the said wipers are in engagement, and trunk conductors 63 and 65 to the upper and lower windings of line relay 70 of the repeater E. The upper winding of line relay 70 being connected to battery by way of the normally closed contacts controlled by armature 80, and resistance 83, line relay 70 energizes over the ground potential coming in over conductor 63, and upon so doing, closes a circuit for release relay 71 at armature 76. Release relay 71, upon energizing, prepares a circuit for relay 74 at armature 77; closes a point in the chain of contacts leading to busying conductor 59 at armature 79; and at armature 78 places ground upon conductor 64, thereby establishing the usual holding circuit for switching relay 50 of the switch C. This, of course, occurs before the slow acting line relay 51 has had time to deener-

gize. It will be noted that when ground is placed upon conductor 64, a circuit is closed for the lower or polarizing winding of the electropolarized relay 72. This winding alone, however, consisting of few turns of high resistance is not able to energize the relay.

As a result of the energization of line relay 70, it closes a bridge across the conductors of trunk line X as follows: from the lower conductor of trunk line X, by way of impedance 73, upper winding of electro polarized relay 72, resting contact of armature 82 and said armature, and armature 75 of line relay 70 and its working contact. In the distant office, the line and release relays of the selector D now energize in response to the closure of this bridge and prepare the switch for operation in the usual manner. Current is now flowing through the upper winding of electro polarized relay 72, but in a direction opposite to that in which it is flowing in the lower winding and consequently the relay is not energized for the time being. The repeater E is now ready to repeat impulses to the selector D which is ready for operation.

Going back now to the point at which the circuit for the indicating lamp L^4 , associated with the jack J^2 , Fig. 1, was closed, upon the energization of switching relay 281 of the switch TS, as explained, the operator, upon noting the lighted condition of this lamp, releases the office selecting push button 221, Fig. 5, which she has been holding depressed, and proceeds to set up the remaining digits 4, 5 and 6 of the desired number, the first digit 1 having been taken care of by the depressing of the office push button 221. The operator sets up the second digit 4 by pressing the fourth impulse push button 204, thereby placing battery upon conductor 229, from whence it extends by way of armature 239 and its resting contact, conductor 247, wiper 347, the contact with which it is in engagement, and conductor 155, to a point between relays 123 and 124. The placing of battery upon conductor 155 shunts relay 123 and practically doubles the current flow through relay 124, whereupon the said relay 124 energizes and places ground upon conductor 144 at armature 134. As a further result of the decrease of current flow through relay 123 and the increase of current flow through relay 124, the differentially wound relay 104 becomes sufficiently unbalanced to attract its armature 114, thereby closing a circuit for relay 102. Relay 102, upon energizing, locks itself to the grounded conductor 158 at armature 109 and at armature 110 prepares a circuit for start relay 101.

As a result of ground being placed upon conductor 144 by relay 124, a circuit is closed by way of the working contact of

armature 464 and said armature, and relay 474 to battery. Relay 474, upon energizing, connects the fourth impulse stop conductor 434 with the first digit stop conductor 441 at armature 494, and at armature 449 completes a locking circuit for itself by way of relay 452 and grounded conductor 424 which, as pointed out hereinbefore, is grounded through contacts of relays 410 and 408, Fig. 6, from conductor 167, which is grounded by relay 103, Fig. 4, at armature 111. Relay 452, however, does not energize immediately, owing to the fact that it is short circuited by the ground potential which initially energized relay 474.

The operator now releases push button 204, whereupon battery is removed from conductor 229 and consequently from conductor 155. The differentially wound relay 104, Fig. 4, deenergizes, the balance being restored, and relay 124 falls back, being adjusted so as not to hold up in series with relay 123. Relay 124, upon falling back, opens the initial energizing circuit of relay 474. Fig. 7, but the said relay 474 does not deenergize, being maintained energized over its previously pointed out locking circuit including relay 452. Relay 452, upon energizing in response to the opening of the initial circuit of relay 474, opens the circuit of relays 453 and 454 at armature 459, whereupon the said relays deenergize and at armatures 461-470, inclusive, disconnect the relays 471-480, inclusive, from the set up conductors 141-150, inclusive. As a further result of the energization of relay 452, it places ground upon conductor 169 at armature 460, by way of armature 457 and its resting contact. This, however, does not produce any effect for the time being. As a still further result of the energization of relay 452, it places ground upon conductor 524 at armature 481, thereby closing a circuit for relays 553 and 554, Fig. 8, by way of the resting contact of armature 559 and said armature. Relays 553 and 554, upon energizing, connect up the set up conductors 141-150, inclusive, with the relays 571-580, inclusive, respectively, at armatures 561-570, inclusive. The second digit storage equipment is now in condition to receive the second digit as it is set up by the operator.

The operator now depresses the fifth impulse push button 205 for the third digit 5 of the desired number, thereby placing ground upon conductor 230, which ground extends by way of armature 238 and its resting contact, conductor 248, wiper 346, conductor 154, to a point between relays 125 and 126, thereby short circuiting relay 126 and permitting relay 125 to energize. Relay 125, upon energizing, closes the following circuit: from ground by way of the working contact of armature 135 and said armature

conductor 145, working contact of armature 565 of relay 554 and said armature, Fig. 8, and relay 575 to battery. Relay 575, upon energizing, connects the fifth impulse stop conductor 435, with the second digit stop conductor 542 at armature 595, and at armature 549 closes a locking circuit for itself, including relay 552 and grounded conductor 524. Relay 552, however, does not energize for the time being owing to the fact that it is short circuited by the ground potential which caused the initial energization of relay 575.

The operator now releases the fifth impulse push button 205, whereupon ground is removed from conductor 230, and relay 125 falls back. Upon falling back, relay 125 opens the initial energizing circuit of relay 575, Fig. 8, at armature 135. Relay 575, however, does not deenergize but is maintained energized over its locking circuit which includes the grounded conductor 524, relay 552, and armature 549 and its working contact. Relay 552, upon energizing in series with relay 575, opens the circuit of relays 553 and 554 at armature 559, whereupon the said relays deenergize and disconnect conductors 141-150, inclusive, from relays 571-580, inclusive. As a further result of the energization of relay 552, it places a multiple ground upon conductor 169 at armature 560, by way of armature 557 and its resting contact; and at armature 581 places ground upon conductor 582, thereby closing a circuit for the relays in the fourth digit storage set corresponding to relays 553 and 554, which set is not shown but which is identical with the storage set shown in Fig. 8. When this occurs, the conductors 141-150, inclusive, are connected up to the set up relays of the fourth digit set up set.

The operator now depresses the sixth impulse push button 206, thereby placing battery upon conductor 230, shunting relay 125, Fig. 4, and allowing relay 126 to energize. Relay 126, upon energizing, places ground upon conductor 146 at armature 136, whereupon the sixth set up relay in the fourth digit storage set, (not shown) energizes and connects the sixth impulse stop conductor 436, Fig. 8, with the fourth digit stop conductor, (not shown).

When key 206 is released, the balance is again restored to relays 125 and 126, whereupon relay 126 deenergizes and removes ground from conductor 146 at armature 136. When this occurs, the previously described relay operations take place in the fourth digit storage set with the result that the sixth set up relay in that set remains locked up and the conductors 141-150, inclusive, are disconnected from the set up relays of said storage set.

The operator, having finished setting up the number, which, although it has taken

some time to describe, requires but a trivial amount of time, inserts the calling plug P' of the cord circuit O into the proper jack J^2 , as indicated by the lighted condition of the lamp L^4 . When this occurs, sleeve relay 26 energizes over sleeve conductor 11 in series with supervisory lamp L^2 and the said lamp L^2 becomes lighted. Sleeve relay 26, upon energizing, closes a circuit for the upper winding of marginally adjusted relay 27 at armature 34, which circuit includes the resting contact of armature 30 and said armature. The upper winding of relay 27 comprises a small number of turns and has a high resistance, and consequently has only a weak pull at this time. This relay is adjusted so as to pull the armature 37 over against its working contact, but not to operate either armature 36 or armature 38. As a further result of the energization of sleeve relay 26, it prepares a locking circuit for the marginally adjusted relay 25 at armature 33, and at armature 35 connects relay 25 in series with high wound relay 269 of the switch SS, Fig. 5, by way of the following circuit: from ground by way of relay 269, armature 211 and its working contact, wiper 303 and the contact with which it is in engagement, conductor 307, resting contact of armature 31 and said armature, armature 35 and its working contact, and relay 25 to battery. Relay 269 energizes over this circuit, but relay 25, being marginally adjusted, is not able to energize on account of the high resistance of relay 269. Relay 269 which not only has a high resistance, but also is efficiently wound, is adjusted very stiffly with the exception of armature 277 which is given a very weak adjustment. Accordingly, when the circuit of the said relay 269 is closed, armature 277 makes contact with its working contact immediately, but there the movement stops for an interval until the magnetic circuit is built up to a point near its maximum, which requires an appreciable length of time.

Armature 277, upon coming into engagement with its working contact, closes a circuit for start relay 101 as follows: from ground by way of the working contact of armature 277 and said armature, working contact of armature 273 and said armature, conductor 249, wiper 349 and the contact with which it is in engagement, conductor 157, armature 110 and its working contact, and start relay 101 to battery. Start relay 101, which is designed and adjusted so as to energize very quickly and which energizes fully before relay 269 of the switch SS has pulled its armatures all the way up, upon energizing, completes a locking circuit for relay 103 at armature 105, disconnects conductor 151 from set up release conductor 166 and connects it to impulse conductor 165 which is grounded at this time

by way of armatures 416 and 419, Fig. 6. As a further result of the energization of start relay 101, it connects the grounded conductor 424 with holding conductor 158 and disconnects the latter from the circuit of relay 103 at armature 106, thereby furnishing ground to hold up the various relays of the switches SS and TS as will be hereinafter explained. As a still further result of the energization of start relay 101, it connects ground, by way of the grounded conductor 169, with start conductor 168 at armature 107, thereby starting operations in the counting switch CS, Fig. 6, in a manner to be explained fully hereinafter.

Returning now to relay 269 of the switch SS, Fig. 5, the said relay upon finally pulling all the way up, opens the local holding circuit of relay 268 at the normally closed contacts controlled by armature 277, but the said relay 268 remains energized over a circuit which includes holding conductor 158 and armature 274 and its working contact. It will be remembered of course, that holding conductor 158 was grounded, as explained, by the energization of start relay 110, Fig. 4. As a further result of the energization of relay 269, it closes a circuit for push button switching relay 251 at armature 278, the said circuit including the working contact of armature 288 and said armature. Switching relay 251, upon energizing, disconnects conductors 225 and 226 and 228-233, inclusive, from the trunk selecting and sender selecting set shown, and connects them by way of conductors 254-261, inclusive, to a reserve set, which is an exact duplicate of the one shown, with the one exception that the armature in the reserve set, which corresponds to armature 278 of relay 269, controls a normally closed point in the circuit of relay 251 instead of a normally open point, for a reason which will be explained fully hereinafter. In case the operator receives another call at this time, she operates the push buttons in the usual manner and the call is set up on the reserve set. As a still further result of the energization of relay 269, it places a shunt around armature 276 and its working contact at armature 293; and at armature 279 alters the circuit of the upper winding of line relay 70 of the repeater E, so that instead of being grounded by way of the normally closed contacts controlled by armature 279, the circuit of the said relay extends as follows: from ground by way of the resting contacts of armatures 416 and 419 and said armatures, Fig. 6, impulse conductor 165, working contact of armature 108 and said armature, conductor 151, the contact in the bank of the switch SS in which said conductor terminates, wiper 343, conductor 243, armature 279 and its work-

ing contact, and thence by way of a previously traced circuit, including the upper winding of line relay 70 of the repeater E, to battery.

5 Returning now to the operation of the counting switch CS, Fig. 6, in response to the placing of ground upon start conductor 168, by the energization of start relay 101, Fig. 4, relay 409 energizes; closes a circuit for relay 410 at armature 421; and brings armature 422 into engagement with its working contact. Relay 410, upon energizing, alters the connection between conductors 167 and 424 so as to include armature 422 and its 10 working contact and armature 423 and its working contact instead of the normally closed path shown. As a further result of the placing of ground upon start conductor 168, impulse relay 407, which is connected 15 with start conductor 168 by way of armature 415 and its resting contact and which is intermittently connected to battery by way of contacts 412, begins to energize and deenergize once during each revolution of the revolving motor driven cam 411, which cam is 20 revolving at the correct speed to energize and deenergize impulse relay 407 at the most efficient speed for the switch operation. Relay 407, upon energizing the first time, disconnects impulse conductor 165 from ground at armature 419. This, however, does not produce any effect owing to the fact that the said conductor is still grounded by way of armature 416 of pick up relay 406 and its 25 resting contact. As a further result of the energization of relay 407, it closes a circuit for stepping magnet 403 at armature 418. Stepping magnet 403, upon energizing, attracts its armature thereby causing the pawl 30 of said armature to engage another notch on the wiper driving ratchet wheel (not shown). Upon deenergizing, relay 407 opens the circuit of stepping magnet 403 at armature 418, whereupon the wipers 401 and 402 are 35 advanced under spring tension into engagement with the first set of bank contacts. Wiper 401, upon coming into engagement with the first contact in its associated bank, which contact is grounded, as shown, closes a circuit for pick up relay 406. Pick up relay 406, upon energizing, prepares a locking circuit for relay 405 at armature 417, and at 40 armature 416 removes the shunt from around armature 419 and its resting contact. The next time that relay 407 energizes, it closes a circuit for stepping magnet 403, which 45 magnet attracts its armature in the usual manner, and at armature 419, relay 407 opens the circuit of line relay 70 of the repeater E, Fig. 2. When the following deenergization of impulse relay 407 occurs, the 50 circuit of line relay 70 of the repeater E is closed again at armature 419 and the circuit of stepping magnet 403 is again opened at armature 418. Stepping magnet 403, upon 55 deenergizing, advances the wipers 401 and 402 into engagement with the second set of bank contacts. The advancing of wiper 401 obviously does not produce any result at this time as the second contact in its bank is 60 grounded also. Wiper 402, by coming into engagement with its second contact, connects stop relay 405 with its first impulse stop conductor 431. This does not produce any result, however, owing to the fact that conductor 431 is not grounded at any point. The operation of relay 407 and stepping magnet 403 continues uninterrupted until the wiper 402 arrives upon the bank contact 444 in which the fourth impulse stop conductor 434 65 terminates, at which time the circuit of line relay 70 of the repeater E, Fig. 2, will have been interrupted four times.

When wiper 402 arrives upon bank contact 444 in response to the deenergization of stepping magnet 403, stop relay 405 is energized over the following circuit: from ground by way of armature 456 of relay 450, Fig. 7, and its resting contact, second digit stop conductor 441, working contact of armature 494 and said armature, fourth impulse stop conductor 434, bank contact 444, wiper 402, and stop relay 405 to battery. Stop relay 405, upon energizing, completes a locking circuit for itself at armature 414; 70 disconnects impulse relay 407 while it is in a deenergized condition, at armature 415; and at armature 413 connects stepping magnet 403 in multiple with relay 406 at armature 413. Stepping magnet 403 now buzzes rapidly, its circuit being intermittently opened and closed at armature 404, thereby advancing the wipers 401 and 403 step by step until the wiper 401 arrives upon the ungrounded contact 450, and wiper 402 upon contact 75 452. When this occurs, the circuit of pick up relay 406 is opened and the operation of stepping magnet 403 ceases. Relay 406, being slow-acting, retains its armatures attracted for an interval after its circuit is 80 opened.

As a further result of wiper 402 coming into engagement with the grounded contact 444, as previously mentioned, a circuit is closed by way of conductor 425 and armature 455 and its resting contact for relay 451, Fig. 7. Relay 451, upon energizing, closes a locking circuit for itself at armature 458, including relay 450 and the grounded conductor 424. Relay 450, however, does not 85 energize immediately owing to the fact that it is short circuited at this time.

After a short interval slow-acting relay 406 deenergizes, thereby replacing the shunt around armature 419 and its resting contact 90 at armature 416, and at armature 417 removes direct ground from conductor 425, whereupon relay 450, Fig. 7, energizes over a circuit which includes relays 405 and 451 in multiple and, upon so doing, removes ground 95

from conductor 169, at armature 457, leaving the said conductor grounded in the third and fourth digit storage sets. As a further result of the energization of relay 450, it disconnects ground at armature 456, from the second digit stop conductor 441 and places it upon the third digit stop conductor 542, Fig. 8, by way of conductor 523 and armature 556 and its resting contact; and at armature 455 disconnects relay 405 from in multiple with relay 451 and connects it, by way of conductor 525, in multiple with the corresponding relay 551 of the third digit storage set, Fig. 8. When this occurs, the circuit of relay 405 is finally opened. Relay 405, being slow acting retains its armatures attracted for an interval after which it falls back and connects up impulse relay 407 at armature 415, thereby starting the counting switch CS so as to produce the second series of interruptions in the impulse circuit. It will be noted that there is an interval of time, between the sending of the last impulse in the first series and the starting of the counting switch CS for the second series, determined by the length of time required for the slow acting relays 406 and 405 to fall back one after the other. This, it may be stated, is done so as to give the automatic switches time to effect the change over and the trunk hunting operations.

In response to the falling back of relay 405, relay 407 is connected up at armature 415 as before stated, and accordingly begins to energize and deenergize again. On the first energization of relay 407, stepping magnet 403 is energized and, upon the subsequent deenergization of relay 407, stepping magnet 403 is deenergized, and wiper 401 is advanced from contact 450 into engagement with a grounded contact, whereupon pick up relay 406 energizes, thereby preparing a locking circuit for stop relay 405 and removing the shunt from around armature 419 and its resting contact. When relay 407 is energized again, the impulse circuit is opened at armature 419, in addition to the closing of the circuit of stepping magnet 403 at armature 418, and, upon the subsequent deenergization of relay 407, the impulse circuit is again closed and stepping magnet 403, upon deenergizing, advances the wiper 402 into engagement with bank contact 451 with which the first impulse stop conductor 431 is connected. This does not produce any effect at this time for the reason that the first impulse stop conductor 431 is not grounded at any point. The operation of relay 407 and stepping magnet 403 continues as described until wiper 402 is advanced into engagement with bank contact 445, at which time the impulse circuit will have been opened five times.

When wiper 402 comes into engagement with bank contact 445, the following circuit

is closed for stop relay 405: from ground by way of the third digit stop conductor 542, Fig. 8, working contact of armature 595, fifth impulse stop conductor 435, bank contact 445, Fig. 6, wiper 402, and stop relay 405 to battery. A branch of this circuit extends by way of conductor 425, armature 455 and its working contact, conductor 525, armature 555 and its resting contact, and relay 551 to battery. Relay 551, upon energizing, closes a locking circuit for itself including relay 550 and the grounded conductor 524, at armature 558. Relay 550, however, does not energize for the time being, owing to the fact that it is short circuited. Stop relay 405, Fig. 6, upon energizing disconnects relay 407 at armature 415, closes a locking circuit for itself at armature 414, and closes the automatic stepping circuit of stepping magnet 403 at armature 413. The wipers 401 and 402 are now advanced in a previously described manner by the buzzer like action of stepping magnet 403 until the wiper 401 becomes into engagement with the last bank contact, which contact is ungrounded. When this occurs, the circuit of slow acting relay 406 is opened. Upon deenergizing, after an interval, relay 406 places a shunt around armature 419 and its resting contact at armature 416, and at armature 417 removes direct ground from conductor 425, whereupon relay 550, Fig. 8, being no longer short circuited, energizes in series with relay 551 and removes ground from conductor 169 at armature 557, leaving the said conductor grounded only in the fourth digit set up set (not shown). As a further result of the energization of relay 550, it disconnects conductor 523 from the third digit stop conductor 542 and connects it with conductor 583; and at armature 555 disconnects conductor 525 from relay 551 and connects it to the corresponding relay in the fourth digit set up set by way of conductor 584.

Slow acting relay 405, upon deenergizing in response to the opening of its circuit, which is finally accomplished by the energization of relay 550, Fig. 8, at armature 555, as described, connects up impulse relay 407 again at armature 415, whereupon the counting switch CS begins to operate in the previously described manner, with the result that the impulses of the fourth digit of the number are sent out at armature 419. In this case the impulses are terminated by wiper 402 coming into engagement with bank contact 446 with which the sixth impulse stop conductor 436 is connected, it being remembered of course, that the sixth stop conductor 436 is grounded in the fourth digit set up set.

In response to wiper 402 coming into engagement with the grounded contact 446, stop relay 405 is energized in the usual man-

ner and the relay in the fourth digit set up set which corresponds to relay 551, Fig. 8, is energized, and in response to the removal of direct ground from conductor 425 by 5 the deenergization of pick up relay 406 which occurs subsequently, the relay in the fourth digit set up set which corresponds to relay 550, Fig. 8, energizes and at an armature, which corresponds to armature 557, 10 disconnects ground from conductor 169. Since the ground has already been removed from conductor 169 in the second and third digit set up sets, this operation leaves conductor 169 ungrounded. The removal of 15 ground from conductor 169 removes the ground potential from start conductor 168 and consequently there is no circuit closed for impulsing relay 407 when it is connected up at armature 415 by the subsequent de- 20 energization of stop relay 405.

Before going further, the operation of the automatic switches, Figs. 2 and 3, which occurs in response to the several series of interruptions produced in the circuit of line 25 relay 70 of the repeater E, as explained, will be taken up. In response to the first series of interruptions, which comprises four interruptions, produced in its circuit, which owing to the fact that the first digit 1 of 30 the desired number is determined by which trunk selecting switch TS or TS', Fig. 5, is operated, corresponds to the second digit 4 of the desired number, line relay 70 of the repeater E deenergizes four times momentarily, thereby interrupting the bridge across the trunk line X four times, at armature 75. Upon energizing in response to the closing of its circuit, upon the falling back of armature 76 of line relay 70, relay 74 shifts the 35 bridge across the conductors of the trunk line X so as to exclude the impedance 73 and the upper winding of relay 72. This is the usual expedient made use of in order to obtain first-class switch control. Relay 74, being slow-acting, retains its armatures attracted throughout the series of interruptions and falls back upon the termination thereof. In response to the four interruptions produced in the bridge across the 40 trunk line X, the selector D operates in the well known manner to raise its shaft and wipers to the fourth level and rotate them in search of an idle connector switch. Assuming that the connector H is the one selected, the line and release relays thereof 45 energize, thereby preparing the switch for operation in the usual manner.

In response to the next series of five interruptions produced in the circuit of line 50 relay 70 of the repeater E, the bridge across the conductors of the trunk line X is interrupted five times, whereupon the connector H in the distant exchange raises its shaft and wipers until the latter stand opposite 55 the fifth level of bank contacts.

In response to the next and last series of interruptions produced in its circuit, which series comprises six interruptions, line relay 70 of the repeater E interrupts the bridge across the conductors of the trunk 70 line X six times, whereupon the wipers of the connector H in the distant exchange are rotated into engagement with the sixth set of contacts in the fifth level, which set is the one shown in the drawings. The connector H, through circuits which are not shown, now begins to project ringing current out over the called line, thereby ringing the bridged bell at the called substation A intermittently. 75

Returning now to the sending equipment, Fig. 6, in response to the removal of ground from start conductor 168 which is effected, as before explained, upon the termination of the last series of impulses, relay 409 de- 80 energizes, thereby opening the circuit of relay 410 at armature 421. Relay 410, however, being slow acting, retains its armature 423 attracted for an interval after which it falls back. As a further result of the de-energization of relay 409, it disconnects conductor 167 from conductor 424 at armature 422, thereby removing the ground potential from conductor 424. When the ground potential is removed from conductor 424, relays 450-452, inclusive, and relay 474, Fig. 7, deenergize. Relay 452, upon deenergizing, removes ground from conductor 524 at armature 481, whereupon the corresponding relays 550-552, inclusive, Fig. 8, and relay 575, deenergize. Relay 552, upon deenergizing, removes ground from conductor 582 at armature 581, whereupon the corresponding relays in the fourth digit set up set deenergize. As a further result of the removal of ground potential from conductor 424, ground is removed from the holding conductor 158, Figs. 4 and 5, which conductor is at this time connected with conductor 424 by way of armature 106 and its working contact, Fig. 4. When the ground potential is removed from holding conductor 158, relay 102, Fig. 4, deenergizes; disconnects itself from conductor 158 at armature 109; and opens the circuit of start relay 101, at armature 110, whereupon the said start relay 101 deenergizes and opens the locking circuit of relay 103 at armature 105. Relay 103, upon deenergizing, opens the circuit of differentially wound relay 104 and relays 121-130, inclusive, at armature 113. The sender shown is now at normal. 100

As a still further result of the removal of ground from holding conductor 158, which occurs as pointed out before, switching relay 268 of the sender selector SS deenergizes; opens the initial locking circuit of the lower winding of relay 280 of the switch TS at armature 276, leaving the said locking circuit closed at armature 293; discon- 105 110 115 120 125 130

nects wiper 349 at armature 273, opens a further point in its own circuit at armature 274; and at armature 275 places the upper portion of the winding of relay 269 in multiple with the lower portion of the winding. When this occurs, the marginally adjusted relay 25 in the trunk circuit T, Fig. 2, energizes; closes a locking circuit for itself at armature 29, connects trunk conductor 12 through to the lower winding of line relay 70 at armature 32; thereby completing the following circuit: from ground by way of resistance 84 in the repeater E, resting contact of armature 81 and said armature, lower winding of line relay 70, conductor 65, wiper 62, working contact of armature 32 and said armature, conductor 12, and thence to battery by way of supervisory relay 8 and the lower right hand winding of the associated repeating coil. Supervisory relay 8, however, does not energize over this circuit on account of the high resistance of the resistance coil 84 in the repeater E. As a further result of the energization of relay 25 it shifts the circuit of the upper winding of line relay 70 at armature 28 so as to include trunk conductor 10, which conductor is grounded by way of the upper right hand winding of the repeating coil in the cord circuit O; opens the circuit of relay 27 at armature 30, whereupon the said relay de-energizes; and at armature 31 opens the circuit of relay 269 of the switch SS. Relay 269, upon deenergizing, opens the circuit of the push button switching relay 251 at armature 278, whereupon the conductors 225 and 226, and 228-233, inclusive, are connected up again to the trunk selecting and sender selecting set shown. As a further result of the deenergization of relay 269, conductor 243 is disconnected from the wiper 302 of the switch TS at armature 279. As a still further result of the deenergization of relay 269, it opens the circuit of the lower winding of relay 280 at armature 293; and at armature 277 closes a circuit for switching relay 268 as follows: from ground by way of the normally closed contacts controlled by armature 277, armature 283 and its working contact, switching relay 268, armatures 265 and 266 and their resting contacts, and relay 267 to battery. The closing of this circuit, however, does not perform any useful function at this time and relay 268, which is slightly slow to pull up on account of having a very stiff adjustment, is not able to energize before its circuit is opened at armature 283 of relay 280, which relay is stiffly adjusted so as to cause it to fall back immediately upon the opening of its circuit. As a further result of the deenergization of relay 280, it opens the circuit of switching relay 281 at armature 286. Switching relay 281, upon deenergizing, disconnects the wipers 301-304, in-

clusive, thereby finally restoring the condition of the trunk selecting and sender selecting apparatus to normal.

When the called subscriber responds to the ringing of his bell by removing his receiver, a direct current bridge is closed across the conductors of his line, whereupon the connector H operates in the well known manner to remove ringing current from the called line and to connect up the back bridge relay 86 with the latter. Back bridge relay 86, upon energizing over the called line, reverses the incoming trunk conductors as regards their connection with the line relay, whereupon the upper winding of electropolarized relay 72 of the repeater E assists the lower winding in energizing the relay.

Electropolarized relay 72, upon energizing, disconnects resistance 84 from the lower winding of line relay 70 at armature 81, and at armature 80 connects the lower and upper windings of line relay 70 in series and at the same time disconnects battery through the resistance 83 from the latter winding. Line relay 70 is now bridged across the conductors 63 and 65 and is accordingly held energized over the established connection in series with the right hand windings of the repeating coil in the cord circuit O. When these circuit changes are made, the current flow through the supervisory relay 8 is increased sufficiently to allow it to energize. Upon energizing, supervisory relay 8 places a shunt around the supervisory lamp L² whereupon the said lamp becomes extinguished, giving the operator answering supervision. The calling and called subscribers may now converse with each other as desired, the talking circuit being outlined by the heavy conductors, and after the conversation is finished the two subscribers replace their receivers. When the receiver is replaced at the calling substation A, the circuit of supervisory relay 7 is opened and the said relay, upon deenergizing, removes the shunt from around supervisory lamp L', whereupon the said lamp becomes lighted.

When the receiver is replaced at the called substation A', the circuit of back bridge relay 86 is opened, whereupon the said relay deenergizes, thereby reversing the incoming trunk conductors back to normal. When this occurs electropolarized relay 72 in the repeater E deenergizes, thereby placing battery on the upper winding of line relay 70 through the resistance 83 and ground on the lower winding through resistance 84, and separating the two windings. When this occurs, the supervisory relay 8 in the cord circuit O deenergizes owing to the high resistance 84 in the repeater E, thereby removing the shunt from around supervisory lamp L², whereupon the said lamp becomes lighted.

The operator upon noting the lighted con-

dition of lamps L' and L^2 knows that the conversation is completed and that the calling and the called subscribers have replaced their receivers, and accordingly she pulls down the connection. When the plug is removed from the jack J , cut off relay 5 de-energizes, restoring the calling line to normal condition, and supervisory lamp L' becomes extinguished.

When the plug P' is removed from the jack J^2 the circuit of line relay 70 of the repeater E and of sleeve relay 26 of the trunk circuit T are opened. Sleeve relay 26, upon deenergizing, opens the circuit of relay 25 at armature 33, whereupon the said relay deenergizes. Line relay 70 of the repeater E , upon deenergizing, opens the circuit of release relay 71 at armature 76, and at armature 75 opens the bridge across the conductors of trunk line X . Release relay 71, upon deenergizing, removes ground from release trunk conductor 64 at armature 78, thereby opening the circuit of switching relay 50 of the line switch C , whereupon the said relay deenergizes.

The automatic switches in the distant exchange are released in the well known manner in response to the opening of the bridge across the conductors of the trunk line X by line relay 70 of the repeater E . The entire connection is now released and the apparatus used therein is restored to normal.

Referring now again to Fig. 5, a few points in connection with the apparatus shown there will be considered. It will be remembered that the operator disposes of the first digit of a desired number by depressing one of the keys 221 or 222 which results in the operation of either the switch TS or the switch TS' . It is to be understood that, in case there are more than two automatic offices, as many more trunk selecting switches as needed may be added and that each will be identical with either the switch TS or the switch TS' . It will be understood also that a push button similar to push button 221 or 222 will be added for each of the added trunk selecting switches. Obviously the same addition in trunk selecting switches must be made in the reserve set to which the conductors 252-262, inclusive, extend.

Referring now to the release push button 215, its function will be explained. It sometimes occurs that an operator, in setting up a number, realizes that she has operated the wrong button in which case she will desire to release the part of the number that is stored up and start over again. This she accomplishes by operating the push button 215 which places ground upon conductor 233, thereby closing the following circuit for release relay 408, Fig. 6: from ground by way of conductor 233, armature 235 and its resting contact, conductor 243, wiper 343

and the contact with which it is in engagement, conductor 151, armature 108 and its resting contact, conductor 166, and release relay 408 to battery. Release relay 408, upon energizing, removes ground from conductor 424 at armature 420, whereupon relay 452, which has been energized by a previous operation in series with one of the other relays, relay 474 for example, deenergizes, thereby removing ground from conductor 524 at 53 armature 481, whereupon the corresponding relay in the next storage set, Fig. 8, deenergizes in case it has been operated. Assuming that relay 474 was energized in series with relay 452 the latter relay also deenergized when ground was removed from conductor 424, thereby disconnecting the first digit stop conductor 441 from the fourth impulse stop conductor 434. When the operator releases the release push button, ground is replaced on conductor 424, whereupon relays 453 and 454 energize and connect up conductors 141-150, inclusive, with relays 471-480, inclusive, respectively.

In connection with the reserve set, to which the conductors 252-262, inclusive, Fig. 5, extend, it may be pointed out that switching relay 251, upon energizing in response to the closure of its circuit by relay 269, when the operator plugs in, after having set up a number, switches the set of push buttons over to the reserve set. If the reserve set is not used after this time and before relay 269 deenergizes, after the sending out of the last digit in the desired number, relay 251 deenergizes and connects the set of push buttons to the set shown. However, if the operator gets a second call immediately after having set up the first one and in that case operates one of the push buttons 221 or 222 while switching relay 251 is energized, conductor 262 becomes grounded in the reserve set at an armature corresponding to armature 288 of relay 280, when the associated relay energizes in response to the manipulation of one of the said push buttons 221 or 222, it being remembered of course, that conductor 262 extends to a pair of normally closed contacts in the reserve set instead of a pair of normally open contacts such as are controlled by armature 278 of relay 269. Obviously, in this case relay 251 is held energized until the relay corresponding to relay 269 in the reserve set energizes after the last digit, in the number set up, is sent out.

It will be observed that the wipers 343-348, inclusive, of the switch SS are normally connected to the push buttons 201-210, inclusive, and 215. This however, does not cause any harm to result for the reason that the operator will not manipulate any of these buttons except in the regular course of setting up a connection. However, if she should accidentally operate one of these buttons no harm would result because they are

disconnected at armatures 252' and 253' of relay 268. Of course it is possible that an operator could maliciously interfere with the setting up of a call by another operator by 5 purposely operating two buttons simultaneously, 201 and 203 for example, which would result in connecting conductors 228 and 229 together. This, however, is a very remote possibility. It is obvious that, in case it is 10 deemed advisable in special cases, the conductors leading to the wipers 343-348, inclusive, may be carried through normally open contacts on relay 268 in the same manner as conductor 249, which is connected 15 with wiper 349.

In Fig. 1, the jacks J' and J^2 which are multiplied with the jacks J and J^2 , respectively, are assumed to be at another operator's position. The lamp at the jack J^3 , 20 however, is not multiplied with the lamp L^4 at the jack J^2 , but is connected by way of a conductor, corresponding to conductor 305, to the bank of the trunk selecting switch at 25 that position corresponding to the trunk selecting switch TS, Fig. 5. These two lamps are connected on separate circuits in order to prevent confusion which would result if 30 they should both light when it is desired to make an indication to an operator at one position only.

Referring now to the marginally adjusted relay 27 in the trunk circuit T, Fig. 2, the function of this relay will be explained. It will be remembered that when sleeve relay 35 26 energizes in response to the operator plugging in after having set up a number, in addition to causing the sender to begin 40 to send out the impulses to operate the automatic switches, the said relay 26 closes a circuit for the upper winding of relay 27 at armature 34, whereupon the said relay 27 energizes just sufficiently to operate armature 37, thereby closing a locking circuit for 45 itself through its lower winding. The lower winding, however, is ineffective for the time being owing to the fact that it is short circuited. In the usual course of operation the sending is uninterrupted and when relay 25 50 energizes after the last digit is sent out the circuit of the upper winding of relay 27 is opened at armature 30 and the said relay deenergizes. However, it may occur that the operator will pull the plug P' from the jack J^2 before the sending is completed. This 55 may result from the hanging up of the calling subscriber, for example.

Without relay 27, in case the operator does pull the plug before the number is completely sent out, the sender is stopped before 60 the sending is completed and a lock up of various relays occurs and the sender is disabled until an attendant clears the trouble. With relay 27 in the circuit, as shown, however, the sender continues to function until 65 the last digit set up is sent out, as will now

be explained. Assuming now that the operator pulls the plug P' from the jack J^2 before the sender has sent the last digit of the number and consequently before relay 25 has energized. Sleeve relay 26, upon de- 70 energizing, opens the initial circuit of the upper winding of relay 27 at armature 34, thereby removing the short circuit from the efficiently wound lower winding of the said relay 27. When this occurs, the said relay 27 pulls all the way up; places a shunt around armature 35 and its working contact, of relay 26, at armature 38; and at armature 36 opens the circuit of the upper winding of line relay 70 of the repeater E, whereupon 75 the partly established connection is released.

Armature 35 and its working contact having been bridged, the sender continues to send out the remaining digit in the desired number in the usual manner, but, owing to 80 the operation of relay 27, no result is produced in the automatic switches, and when the last digit has been sent out, relay 25 first pulls all the way up in the usual manner, and then, since sleeve relay 26 is 85 deenergized, the said relay 25 deenergizes because no locking circuit is closed for it.

The various features of the invention having been described and ascertained in the foregoing will now be pointed out in the 95 appended claims.

What is claimed is:

1. In a telephone system, automatic switches, an operator's position, trunks extending from said position to said switches, a plurality of senders for controlling said switches, a set of number registering push buttons for controlling said senders, a pair of automatic selecting switches individual to said position, and means controlled by the operator for causing one of said selecting switches to select one of said trunks and the other to select one of said senders. 100

2. In a telephone system, automatic switches, an operator's position, a plurality of groups of trunks extending therefrom to said switches, a plurality of operators' senders for controlling said switches, a set of number registering push buttons, another set of push buttons comprising a push button 105 for each of said groups of trunks, a sender selecting switch associated with said groups of push buttons, a plurality of trunk selecting switches associated with said groups of push buttons, one trunk selecting switch for 110 each of said groups of trunks and corresponding thereto, and means controlled by the operation of one of said push buttons in the second mentioned group for causing the trunk selecting switch associated therewith 115 to select an idle trunk in the associated group and for causing said sender selecting switch to select an idle sender. 120

3. In a telephone system, an automatic switch, an operator's position, a calling line 125

terminating thereat, an idle trunk terminating in said switch, a sender, means for connecting said sender with said idle trunk, means whereby an operator at said position may store up a number in said sender, means whereby the operator can connect said calling line with said trunk, and means responsive thereto for causing said sender to transmit the stored up number over said trunk.

4. In a telephone system, a call sender, a plurality of groups of trunk lines, a plurality of operator's devices, one for each of said groups of trunk lines, and automatic switching mechanism responsive to the actuation of any one of said devices for connecting said sender to an idle trunk line in the group corresponding to the actuated device.

5. In a telephone system, a plurality of call senders, a plurality of groups of trunk lines, means for connecting an idle sender to an idle trunk line in any desired group, said means comprising a link circuit terminating at one end in a sender selecting switch and at the other end in a plurality of trunk hunting switches, one for each group of trunk lines, and means controlled by an operator for starting said sender selecting switch and any desired trunk hunting switch.

6. In a telephone system, a plurality of call senders, a plurality of groups of trunk lines, means for connecting an idle sender to an idle trunk line in any desired group, said means comprising a link circuit terminating at one end in a sender selecting switch and at the other end in a plurality of trunk hunting switches, one for each group of trunk lines, a plurality of operator's devices, one for each of said groups of trunks and means responsive to the actuation of any device for starting said sender selecting switch and the corresponding trunk hunting switch.

7. In a telephone system, a plurality of call senders, a plurality of groups of trunk lines, means for connecting an idle sender to an idle trunk line in any desired group, said means comprising a link circuit terminating at one end in a sender selecting switch and at the other end in a plurality of trunk hunting switches, one for each group of trunk lines, means controlled by an operator for starting said sender selecting switch and any desired trunk hunting switch, and means operated after a trunk line is found for indicating the selected trunk to the operator.

8. In a telephone system, a plurality of call senders, a plurality of groups of trunk lines, means for connecting an idle sender to an idle trunk line in any desired group, said means comprising a link circuit terminating at one end in a sender selecting switch

and at the other end in a plurality of trunk hunting switches, one for each group of trunk lines, means controlled by an operator for starting said sender selecting switch and any desired trunk hunting switch, and means operated responsive to the completion of both the sender selecting and the trunk selecting operations for indicating the selected trunk to the operator.

9. In a telephone system, a plurality of call senders, a plurality of groups of trunk lines, means for connecting an idle sender to an idle trunk line in any desired group, said means comprising a link circuit terminating at one end in a sender selecting switch and at the other end in a plurality of trunk hunting switches, one for each group of trunk lines, means controlled by an operator for starting said sender selecting switch and any desired trunk hunting switch, multiple jacks and signals for said trunk lines at the operator's position, and means operated automatically when a trunk is found for operating the signal associated therewith.

10. In a telephone system, a plurality of "A" operators' positions, a plurality of groups of trunk lines multiplied at all of said positions, a plurality of call senders, a link circuit individual to each position, and automatic switching mechanism included in each link circuit for selecting an idle sender and for associating the same with an idle trunk line in any desired one of said groups.

11. In a telephone system, a plurality of "A" operators' positions, a plurality of groups of trunk lines multiplied at all of said positions, a plurality of call senders, a link circuit individual to each position, automatic switching mechanism included in each link circuit for selecting an idle sender and for associating the same with an idle trunk line in any desired one of said groups, a reserve link circuit at each position similar to said first mentioned link circuit, and means for rendering the reserve link circuit at any position operative whenever the other link circuit at such position is in use.

12. The combination, with a register, of means for setting the same comprising a group of ten digit keys, a group of ten digit relays, and circuit arrangements comprising only five conductors connecting the said keys with the said relays whereby the actuation of any key will cause the energization of the corresponding relay.

13. In a telephone system, a plurality of groups of conductors each terminating in a set of stationary contacts, a set of wipers for selecting a set of said contacts, a plurality of switch mechanisms each for driving one of said wipers, motor magnets for said mechanisms, and means for operating all of said motor magnets simultaneously and in synchronism with each other.

14. In a telephone system, an operator's switchboard, a plurality of automatic switches, a plurality of trunks extending from said switchboard to said switches, a plurality of senders for controlling said switches, switching means for the individual use of the operator at said switchboard comprising a sender selector having access to said senders and a trunk selector having access to said trunk lines, operator controlled means for simultaneously starting both of said selectors to cause the said switching means to associate a selected idle sender with a selected idle trunk line, means for indicating the selected trunk to the operator, a key set normally associated with said switching means operable for setting the selected sender in accordance with the number of the called line, operator's equipment for connecting the calling line with the selected trunk, and means responsive to the completion of such connection for starting the operation of the selected sender.
15. In a telephone system, an operator's switchboard, a plurality of automatic switches, a plurality of trunks extending from said switchboard to said switches, a plurality of senders for controlling said switches, switching means for the individual use of the operator at said switchboard comprising a sender selector having access to said senders and a trunk selector having access to said trunk lines, operator controlled means for simultaneously starting both of said selectors to cause the said switching means to associate a selected idle sender with a selected idle trunk line, means for indicating the selected trunk to the operator, a key set normally associated with said switching means operable for setting the selected sender in accordance with the number of the called line, operator's equipment for connecting the calling line with the selected trunk, and means responsive to the completion of such connection for starting the operation of the selected sender.
16. In a telephone system, an operator's switchboard, a plurality of automatic switches, a plurality of trunks extending from said switchboard to said switches, a plurality of senders for controlling said switches, switching means for the individual use of the operator at said switchboard comprising a sender selector having access to said senders and a trunk selector having access to said trunk lines, operator controlled means for simultaneously starting both of said selectors to cause the said switching means to associate a selected idle sender with a selected idle trunk line, means for indicating the selected trunk to the operator, a key set normally associated with
17. In a telephone system, an operator's switchboard, a plurality of groups of trunks outgoing from said switchboard, each group for extending calls to a different exchange, a plurality of senders, a link circuit comprising a sender selector at one end having access to said senders and switching mechanism at the other end having access to said trunk lines, means directly controlled by the operator responsive to a call for causing said sender selector to select an idle sender and for causing said switching mechanism to select an idle trunk in the particular group corresponding to the exchange in which the called line is located, operator's equipment for connecting the calling line with the selected trunk line, means for operating the selected sender, and a series of switches controlled by said sender to complete the connection to the called line.
18. The combination, with a pair of relays and a pair of keys, of means for controlling said relays separately by means of said keys over a single conductor, said means comprising a second pair of relays connected in series with a battery, a connection from the junction of said second pair of relays to one end of said conductor, contacts on one key for connecting the other end of said conductor to one pole of said battery, and contacts on the other key for connecting the said other end of said conductor to the other pole of said battery.
19. In a telephone system, a plurality of groups of conductors each terminating in a set of stationary contacts, a set of wipers for selecting a set of said contacts, a plurality of switch mechanisms each for driving one of said wipers, motor magnets for said mechanisms, means for operating all of said motor magnets simultaneously, and means individual to each of said motor magnets for keeping them all in step with each other.
20. In combination, two automatic switches, each of said switches having a wiper and a motor magnet for driving the same in a step by step manner, a circuit for each of said motor magnets, means for closing said circuits simultaneously, and means comprising multiple contacts controlled by

said motor magnets for opening said circuits responsive to the energization of both of said magnets.

21. In combination, two electro-magnets, 5 a circuit for each, means for closing both circuits, and means responsive only to the operation of both of said magnets for opening both of said circuits, said means being non-responsive to the operation of either 10 magnet alone.

22. In a telephone system, a manual switchboard comprising a plurality of operator's positions, a group of trunk lines multiplied at said positions, a plurality of 15 call senders common to said positions, a link circuit individual to each position, and automatic switching mechanism included in each link circuit for selecting an idle sender

and for associating the same with an idle trunk line.

23. In a telephone system, automatic switches, an operator's position, trunks extending from jacks at said position to said switches, a plurality of senders, a pair of automatic selecting switches individual to 25 said position, means controlled by the operator for causing one of said selecting switches to select one of said trunks and the other to select one of said senders, and operator controlled means for setting the selected 30 sender.

In witness whereof, I hereunto subscribe my name this 14th day of January, A. D., 1922.

JOHN WICKS.
